UNITED STATES PATENT OFFICE.

HERMAN HESS, OF INDIANAPOLIS, INDIANA, ASSIGNOR TO JOHN A. KURTZ, OF INDIANAPOLIS, INDIANA.

MAGNETO-GENERATOR.

SPECIFICATION forming part of Letters Patent No. 770,579, dated September 20, 1904.

Application filed November 10, 1903. Serial No. 180,628. (No model.)

To all whom it may concern:

Be it known that I, HERMAN HESS, a citizen of the United States, residing at Indianapolis, in the county of Marion and State of Indiana, 5 have invented certain new and useful Improvements in Magneto-Generators, of which the following is a specification.

In the construction of magneto-electrical generators it is found that there is a considerable leakage of the lines of force around the 10 end of the armature; and the object of my invention is to provide a construction which will in a large measure prevent such leakage.

A further object is to produce a less expensive machine which will still be efficient and neat in appearance.

The accompanying drawings illustrate my invention.

Figure 1 is an axial vertical section. Fig. 2 is an axial horizontal section with the armature removed; Fig. 3, a section on line 3 3 of Fig. 2, and Fig. 4 is a detail.

In the drawings, 10 10 indicate a pair of permanent magnets of the usual form. Se- 25 cured to the adjacent ends of magnets 10 are pole-pieces 11 11, each of which is provided at each end with an overhanging lip 12, as clearly shown in Fig. 4, which is adapted to embrace an inclosing tubular casing 13. Cas- 30 ing 13 is provided at opposite sides in its middle with openings 14, through which the central portions of the pole-pieces 11 may project, the said casing being held in position by the overhanging embracing-lips 12, which 35 are clamped upon the casing by means of a bolt 15. Each end of the casing 13 is closed by a movable head 16, which heads are pro- 40 vided with axial bearings, within which is jour- naled the armature-shaft 17. The casing 13 is made of a comparatively non-magnetic ma- 45 terial—such, for instance, as brass—and thus serves to prevent the lines radiating from the ends of the pole-pieces from passing through the ends of the armature. The shell 13 also 50 serves to inclose the armature and make a practically dust-proof construction.

It will be noticed that the construction de- 55 scribed is exceedingly cheap. The casing 13 may be of commercial tubing, and the pole- pieces 11 are separate from the magnets. Cas- 60 ing 13, with heads 16, forms the main body

of the machine, while the pole-pieces and magnets are held in position by the single bolt 15.

I claim as my invention—

1. In a magneto-generator, the combination, 55 with the magnets, of an armature journaled between the arms thereof, and an inclosing non-magnetic casing surrounding said arma- ture at its ends, said casing being cut away at its middle opposite active portions of the 60 magnet.

2. In a magneto-generator, the combination with the magnet, of the pole-pieces carried thereby, the separate casing 13 mounted be- 65 tween the arms thereof composed of non-mag- netic material, and the armature journaled in said casing.

3. In a magneto-generator, the combination with the magnets and the armature journaled between the poles thereof, of a separate non- 70 magnetic casing interposed between the oppo- site arms of the magnet and surrounding the ends of the armature.

4. In a magneto-generator, the combination of the magnets and pole-pieces thereof having 75 the overhanging lips 12, of the inclosing non- magnetic casing arranged between the arms of the magnet and having cut-away portions through which the main portion of the pole- pieces project, and an armature journaled in 80 said casing, substantially as and for the pur- pose set forth.

5. A magneto-generator consisting of a cen- 85 tral shell having cut-away portions at oppo- site sides of its middle, pole-pieces set in said cut-away portions, a magnet straddling the casing and clamped, upon the pole-pieces, and an armature journaled in said casing.

6. In an electric generator, the combination of a tubular casing having opposite openings 90 in the sides thereof, pole-pieces extending into said casing through said openings, bearing- heads secured to the ends of said casing and an armature journaled in said heads.

In witness whereof I have hereunto set my 95 hand and seal, at Indianapolis, Indiana, this 12th day of October, A. D. 1903.

HERMAN HESS. [L. S.]
